(57) **CLAIM**

The ornamental design for a parrot kite, as shown and described herein.

DESCRIPTION

FIG. 1. Is a perspective view of my parrot kite design;

FIG. 2. Is a top view thereof;

FIG. 3. Is a bottom plan view thereof;

FIG. 4. Is a front view thereof;

FIG. 5. Is a rear view thereof with the tail portions omitted for a clear disclosure of the underlying end configuration; and,

FIG. 6. Is a right side view thereof, the left side view being identical thereto.

The elements shown in broken lines showing are for illustrative purposes only and forms no part of the claimed design.
